GAS DISPENSING DEVICE

William C. Buttner, Winnetka, Ill., assignor to
 The Bastian-Blessing Company, Chicago, Ill.,
 a corporation of Illinois

Application October 3, 1946, Serial No. 700,861

7 Claims. (Cl. 62—1)

1

The present invention relates to liquefied gas dispensing systems and more particularly to a means by which a combustible gas stored in its liquid phase may be vaporized in a novel and improved manner and dispensed at a service pressure for use as a fuel in an appliance.

The petroleum product that this system is designed to handle is preferably a hydrocarbon of the paraffin or olefin series, such as butane, propane or butylene or various mixtures thereof having boiling points below average atmospheric temperature. These fuels are usually stored in their liquid and vapor phases in closed containers and the vapor pressure of the fuel is utilized to move fuel from the container to a point of consumption. In its transition the fuel is expanded, and if not already vaporized, it is vaporized after its preliminary expansion so that the fuel delivered to the appliance is in its vapor phase and at a service pressure.

There are two general types of systems employed. One a "batch" system where vapor fuel is withdrawn from above the liquid in the tank and passed through a pressure reducing regulator to the appliance using the fuel, and the other the so-called "flash" system in which liquid fuel is withdrawn from the bottom of the tank and passed through a pressure reducing regulator and supplied with the latent heat of vaporization to vaporize it at its reduced pressure.

Wherever the vaporization takes place the available heat is absorbed by the gas from its surrounding parts either from its own liquid body or metallic bodies of its controls. In the batch system this heat absorption is largely expended in the tank, whereas with the flash system the heat absorption is confined to a comparatively small area around or beyond the regulator and its connections such as the service line.

The dispensing system of the present invention is similar in many respects to the embodiments disclosed in the copending application Serial No. 539,670 filed by William C. Buttner, Harold L. Norway and Jerome R. Bunce, Jr., June 10, 1944, incorporation of which is hereby made.

One of the objects of the present invention is to provide an improved vaporizer for liquefied petroleum gas wherein the latent heat of vaporization is derived from a controlled catalytic exothermic reaction for standby and peak load operations in an efficient and safe manner.

Another object of the invention is to provide a liquefied petroleum gas vaporizer supplied with the latent heat of vaporization required at any

2

given time throughout winter, summer and gale conditions without freezing up and without going out.

Another object of the invention is to provide an improved flash system whereby two pressure reductions are made on a flowing stream of fuel and heat is supplied to the flowing stream in an improved manner between the two pressure reducers to assure vaporization of the fuel so that only dry gas will be delivered to the consuming appliance.

Another object of this invention is to provide an improved dispensing system in which a portion of the latent heat of vaporization is supplied to the stream of fuel by withdrawing and catalytically oxidizing a minor fraction of said stream to produce heat, and transferring this heat to said flowing stream at a point upstream of the withdrawal point.

Another object of the invention is to establish and utilize a large amount of radiant heat which is transferred from a catalyst bed to a flowing stream of liquefied petroleum gas simultaneously with the convective transfer of heat from the oxidation products passing upwardly through the bed.

A further object of this invention is to provide an improved vaporizer for flash or batch vaporization systems in which no flame or spark is present which might initiate an explosion. The heat of vaporization being obtained by reacting a mixture of fuel and air in such proportions as would be non-explosive.

A further object of the invention is to provide a vaporizer in which the catalyst bed is maintained at the required activation temperature by a smaller pilot heater which is also catalytic.

Another object is to provide a vaporizer having a catalyst bed in which the same kind of fuel as that dispensed is utilized to generate heat, the flow of fuel to said bed being controlled by a temperature responsive valve responsive to the temperature of the flowing stream after the first stage pressure reduction so that large amounts of extraneous heat are supplied only when needed.

These being among the objects of the present invention, other objects will become apparent from the drawing, the description relating thereto and the appended claims.

Referring now to the drawings in which Fig. 1 is a side elevation, partially in section, illustrating an embodiment of the invention in its preferred form.

Fig. 2 is a section showing the insulated cabi-

net and the preferred disposition of the various elements therein.

Fig. 3 is a schematic view of the dispensing system.

Fig. 4 is an enlarged section of the lower portion of the vaporizer, and

Fig. 5 is a section showing one form of a temperature responsive valve.

This invention will be described in connection with a "flash" system of vaporization because its localized latent heat of vaporization requirements are the highest. However, it will be apparent to those skilled in the art that the vaporizing system of this invention may be readily adapted to a batch system and used as a revaporizer to eliminate any condensation formed in the service conduit.

In the flash system liquefied fuel is forced from a storage tank by the vapor pressure of the stored gas and passed through a first stage pressure reducing regulator to reduce its pressure and allow a portion of the fuel to vaporize. Further vaporization occurs to the extent that heat is available at that point in the system to supply the latent heat of vaporization. For the purpose of supplying any deficiency in the available latent heat of vaporization, which may exist beyond the first stage pressure regulator due to a sustained or heavy consumption of gas, a vaporizer is provided which catalytically oxidizes a limited amount of the vaporized fuel to produce the latent heat of vaporization required.

The heat is generated in the vaporizer by a catalytic bed which glows red without flame. The radiant energy of the bed is picked up by a flue having a blackened inside wall and the hot by-products of the oxidation reaction are baffled to contact the flue wall also. In carrying out the preferred form of the invention, the fuel vaporizing coil is spaced from the wall of the flue a distance sufficient for a closed body of fluid, such as air, insulated from outside temperatures, to flow convectively over the outer wall of the flue and then over the coil turns. The coil is shielded from the hot flue at its spaced position by means of a cylindrical sheet of asbestos to assure the convective circulation, and the arrangement prevents moisture collecting around the coils at the same time it also prevents condensation occurring in the flue. Similarly an anti-freeze solution could be employed instead of air.

Referring now to the construction embodying the invention and Fig. 3 particularly, a spherical storage tank 10 is shown in Fig. 1 mounted on hollow legs 11 and 12. One of these legs 12 is provided with a padlocked door 13 affording access to a fitting 14 such as that shown in Patent No. 2,361,865 granted to Harold L. Norway, hereby incorporated by reference. This fitting 14 provides a means for filling the tank 10 as well as withdrawing liquid fuel 15 from the bottom of the tank 10 and includes an excess flow check valve and shut-off valve (not shown). A protective cover 16 is shown on top of the tank 10 which contains a pressure relief safety valve and a liquid level gauge (not shown).

From the fitting 14 a high pressure conduit 17 extends under the ground 18 to a point near a building 20 where it rises into an insulated cabinet containing the pressure reducing regulators 22 and 23, the vaporizer 24 and various controls to be described. A service conduit 25 extends from this cabinet 21 to the appliance 26 using this fuel. A manually operated shut-off valve

27 is provided in this conduit where it enters the building 20.

The disposition of the various elements within the cabinet 21 and the construction of the vaporizer 24 are best shown in Fig. 2. The high pressure conduit 17 enters the cabinet 21 through a hole 28 provided in the bottom and leads to the first stage pressure reducing regulator 22. The intermediate pressure conduit 30 extends upwardly to the temperature responsive valve 31 where the conduit 30 is wound around the temperature sensitive portion of the valve 31 as at 32.

The temperature responsive valve 31 is preferably of the "snap action" type which is fully opened when subjected to a temperature below a certain point and is closed when the temperature is above that point. In some instances, however, a variable valve, such as that illustrated in Fig. 5, has been found desirable.

From the turns 32 the conduit 30 extends downwardly into the vaporizer 24 where it is connected to a heat exchanger coil 33. Another conduit 34 connects the other end of the coil 33 and a trap 35 which serves to collect any unvaporized moisture or heavy fractions preferably at the lowest point in the conduit 36 leading into the service stage regulator 23, which conduit is connected to the regulator by an L fitting 39 in weight supported relationship.

The outlet of the second stage regulator 23 in turn is connected to the service conduit 25 by a T fitting 37 while the remaining opening receives a second T 38 connected by means of a nipple 40. From this second T 38 two conduits 41 and 42 extend downwardly to the bottom of the vaporizer 24. One conduit 41 leads directly to the pilot port 43 and the second conduit 42 is connected to the temperature responsive valve 33 from which the conduit 44 extends to the bottom 45 of the vaporizer 24 where it ends in a gas mixer

An air inlet pipe 46 extends from outside the cabinet 21 to the base casting 47 of the vaporizer 24 and an exhaust pipe 48 extends from the top of the vaporizer 24 to a point outside the cabinet 21. Each of these pipes 46 and 48 is provided with devices such as a caps 50 to allow the passage of gases and prevent the entrance of moisture or snow in the flue 49.

The exhaust pipe 48 is shown in the drawings to lie horizontally. If this pipe 48 were vertical, condensing of moisture in its upper end could drain back into the vaporizer to cool the catalyst bed and stop the reaction. Where operation in cold climates is encountered, it has proved advantageous to have this pipe 48 slope downwardly with the outlet below the top of the vaporizer 24 so that any liquid formed will drain out of the pipe 48. The bottom of the vaporizer 24 comprises a base casting 47 secured to the floor of the cabinet 21. A plurality of tubular shells such as metal housing 52 and an asbestos partition 53 extend upwardly therefrom and receive at their top a closure comprising a casting 51. Two annular spaces 54 and 55 are thus formed by the tubular members, the outer one of which receives the coil 33 against the outer face of the shell 53 and the inner one of which is adjacent to the flue 49. This arrangement allows the convective circulation of antifreeze fluid or air contained in these spaces upward through the inner space over the outer surface of the flue 49 and downward in the outer space over the coil 33. The asbestos shield 53 prevents any substantial amount of heat being absorbed during said upward move-

5

ment of said fluid so that convective circulation is assured and the temperature of the flue wall is kept above the dew point of the hot gases in the flue.

The base casting (Fig. 4), approximately cylindrical in shape, is provided with a hollowed out central portion 56 open at its upper end and apertured to receive the inner end of the air inlet pipe 46. An externally threaded boss 57 is provided at the bottom of this cavity to receive the tube 58 of the mixer 45. A drilled passage 60 extends from a suitable fitting 61 on the side of the casting 47 to the orifice passage 62 which is drilled from the top of the boss 57. The mixing tube 58 extends upwardly through a plate 63 which seals the top of the cavity from the lower end of the flue. The walls of the casting 47 extend upwardly beyond this plate 63 and support a second perforated plate or screen 64 on which the catalyst pellets 65 are retained. An external shoulder 66 on the base casting 47 is also provided which supports the flue 49 and a grooved ring 67 which in turn supports the outer shell 52. The groove 68 in this ring 67 receives the lower end of the baffle shell 53 between the flue 49 and the outer shell 52. The baffle shell 53 carries the heat exchanger coils 33 which may be fastened thereto by brazing or soldering or by other suitable means. In certain applications it has been found desirable to provide a metal baffle shell to support the asbestos partition. In fact an asbestos coating on a metal shell is very good for the partition when the asbestos is located next to the coils 33 to promote the convective circulation of the heat exchange fluid.

A second fitting 70 is screwed into a hole 71 in the side of the casting 47 and a passage 72 connects this hole 71 with a tube 73 leading to the pilot heater 43. This heater 43 consists of a perforated enclosure containing platinized or palladiumized asbestos 74. The annular spaces 54 and 55 may either contain an antifreeze solution or air as a heat transfer medium.

In Fig. 4 the pilot heater 43 is shown supported at the same level with the screen 64 holding the catalyst bed 65, but in some instances it has been found advantageous to locate this heater 43 below the screen 64. A second ring 75 (Fig. 2) is supported by the upper ends of the outer shell 52 and flue 49 and carries the top casting 51 which is hollowed out as indicated to provide communication between the flue and the exhaust pipe 48. The baffle shell 53 is supported in a groove 76 in the ring 75 and is provided with a plurality of holes 77 at the top, as well as a second plurality 78 at the bottom so that the two annular spaces 54 and 55 are in communication with one another at both the top and bottom of the vaporizer 24. This is done so that a convective circulation of air or antifreeze solution will occur through these annular spaces with respect to the flue and the coils 33 when the vaporizer 24 is in operation. A number of horizontal baffle plates 80 are supported by brackets 81 within the flue 49 and serve to inhibit the passage of hot gases through the flue 49 until much of their heat has been transferred to the flue wall.

The mixing tube 58 is so constructed and arranged that a plurality of holes 85 are provided in the side wall of the tube 58 through which air is drawn by both the circulation induced by the pilot heater and the pressurized stream of fuel gas flowing from the tube 58 through the orifice 62. The diameter of this orifice 62 is such that the rate of gas flow after it leaves this tube 58 is

6

greater than the rate of flame propagation of the fuel being used. Thereby ignition in the tube 58 cannot possibly occur even if a flame were introduced from the outside through one of the holes 85. Any flame produced would have to travel upwardly in the tube 58 and would pass the point where the gases are completely mixed. Above this point the mixture, as has been stated, would be too lean to support combustion.

If propane or butane is burned in air, the percentages of fuel to air required for complete flame combustion are respectively 3.85% and 3.08% by volume. If more fuel than this amount is used, it will not be completely burned. The explosive or combustible range of these two gases varies from 2.4% to 9.5% for propane and from 1.9% to 8.5% for butane. The invention operates outside of the range of flame combustion, preferably upon the lean side for the sake of economy.

Referring to the alternate type temperature responsive valve 31a as shown in Fig. 5, this valve depends on the principle of utilizing two metals having different coefficients of thermal expansion to vary the opening position of the valve member 98 with respect to a port 96. The valve 31a comprises a tubular fluid jacket 86 equipped with a fluid inlet 87 and outlet 88. The upper end of this tube is provided with external threads 90 for attachment to the valve body 91. A flexible metallic diaphragm 92 is retained against a shoulder 93 in the body 91 by the end of the jacket 86 and serves to seal the cavity 94 in the valve body 91 from the jacket 86. The other end of the jacket 86 is sealed by a gasketed cap 95. The jacket 86 is made of brass, stainless steel, or other metal having a small coefficient of thermal expansion.

The body 91 is provided with an inlet passage 95 which extends from the top to the valve port 96 opening into the cavity 94. An outlet passage 97 extends outwardly from the chamber 94. The valve member 98 is urged away from the port 96 by a spring 100 which bears against the end of the cavity 94 and a flange 101 on the lower end of the member 98. The upper end of the member 98 is recessed to receive the valve disc 102 which is preferably formed of nylon or a material having similar physical properties.

Disposed within the jacket 86 is the operating member 103, preferably formed of aluminum or other metal having a high coefficient of expansion. The member 103 bears against the lower face of the flexible diaphragm 92 and an adjusting screw 104 provided at the bottom of the jacket 86. The flange 105 is provided to hold the upper end of the rodlike member 103 in axial position.

When this valve 31a is used in the dispensing system, the helix 32 is eliminated and the conduit 30 is connected to the openings 87 and 88 in the jacket 86 so that all fluid passing through the conduit 30 passes through the jacket 86. The passage 95 is connected to the conduit 42, and the outlet 97 is connected to the conduit 44 leading to the mixer 45.

Variations in the temperature of the stream of gas and liquid leaving the first stage pressure reducer 22 cause the member 103 as well as the jacket 86 to expand or contract, but since the coefficients of expansion of the two metals are different, a change in temperature causes the end of the member 103 to assume a varied position with respect to the top of the jacket 86 and the diaphragm 92. Since the diaphragm 92 is flexible this movement is transferred to the

valve member 88 and permits the fuel to flow in varying amounts dependent upon the temperature of the gas in the service line.

The operation of this dispensing system is as follows:

As fuel is consumed by the appliance 28, the vapor pressure of the liquid 18 in the tank 16 forces liquid to pass through the underground conduit 17 to the first stage pressure reducing regulator 22 in the insulated cabinet 21. As the liquid fuel passes through this regulator 22 the pressure is greatly reduced with the result that a portion of the fuel is "flashed" into vapor and simultaneously expanded and chilled. Some heat is supplied at this point to the chilled liquid from the walls of the regulator 22 and conduit 30 to vaporize further fuel. Any fuel remaining unvaporized in the service line passes along with the vapor through the turns 32 surrounding the temperature responsive valve 31 where the temperature sensitive portion of the valve 31 is brought to substantially the temperature of the fuel stream. If the fuel is cold enough, say 40° F. for butane, the valve 31 will be opened to allow a full supply of fuel at service pressure to flow to the catalyzer bed 65 in the vaporizer 24 as controlled by the restricting effect of the passage 82.

After leaving the turns 32 the wet gas stream passes into the heat exchanger coil 33 in the vaporizer 24 where heat is transferred to it by radiation and convective circulation as already described, and the remaining liquid present is vaporized. From the heat exchanger coil 33 the stream passes to the second stage pressure reducing regulator 23 where the pressure is further reduced to service pressure for use in appliances.

On leaving this regulator 23 the major portion of the vapor stream passes through the conduit 25 to the gas consuming appliance 28 within the building 20. A minor portion of the stream passes into the T 38. Two streams of gas leave this fitting 38. One stream flows at a rate of approximately one tenth of a cubic foot per hour through the conduit 41 to the pilot heater 74. The volume supplied to this catalytic heater 74 is just sufficient to maintain a portion of the main catalyst bed 65 above the activation temperature or that temperature at which catalytic combustion will occur. This temperature varies according to the fuel dispensed, but a temperature well above the minimum requirement is preferably provided. A temperature of 600° F. localized in a small area has proved satisfactory. In all cases the temperature provided is considerably below the ignition temperature of the fuel, so that the danger of overheating and ignition or flame combustion is entirely eliminated.

A second stream of gas leaving the T fitting 38 passes through the temperature responsive valve 31, during the time that this valve is opened, to the main supply mixer 45 of the vaporizer 24. The gas stream enters the mixer 45 through the passage 80. The rate of flow through this passage is regulated by the size of the orifice 62 and the pressure setting of the second stage regulator 23. A constant velocity stream of gas therefore passes upwardly through the tube 58. Air enters through the holes 85 and is mixed with the gas stream in the tube 58. The mixture then passes through the catalyst bed 65 where it is oxidized to release heat and hot gases upwardly into the flue 49. Radiant heat 75

from the glowing bed warms the wall of the flue and the passage of the hot gases is slowed down by the baffles 86 so that their heat is transferred to the walls of the flue 49. Thus the air or antifreeze solution in the annular space 55 is heated. This heat transfer medium rises by convection to the top of the space 55 where it passes through the holes 77 into the outer annular space 54 flowing downwardly over the coils 33 and heating the stream of fuel flowing through them. The descending cooled medium then passes inwardly through the holes 78 at the bottom and back into the inner space 55 where it is reheated. The recirculation of the same medium, in event it is air as shown, avoids condensation problems. Furthermore, the fact that the hot gases do not come into direct heat exchange contact with the cold coil 33 eliminates condensation in the flue.

In view of the fact that the pressure in the conduits and coil between the first and second stage regulators is governed by the first stage regulator and is constant, the temperature of the stream of vapor and liquid flowing through these conduits is constant as long as unvaporized liquid is present in the stream. Any heat applied will merely serve to vaporize liquid rather than raise the temperature. Thus, heat can be supplied as long as liquid is present in the line at a constant temperature setting.

Consequently, it is possible to use a temperature actuated valve 31a which does not have a snap action and still achieve a substantially constant rate of flow of fuel to the burner 45 at the vaporizer 24. This is accomplished by using a valve such as that shown in Fig. 5 having a port 88 at a relatively large cross sectional area compared with the area of the orifice 62 in the mixer 45. By this means a very slight opening of the valve 31a allows sufficient fuel to pass that no appreciable pressure drop occurs in the valve 31a.

In practice the pressure at which the temperature responsive valve 31 opens is set at a value a few degrees above the equilibrium temperature for saturated vapor of the fuel being used at the pressure setting of the first stage regulator 22.

Therefore, when no fuel or only a small amount is being used in the appliance 28, the rate of heat transfer through the walls of the regulator 22 and the conduit 30 is sufficient to supply all the latent heat of vaporization required and the fuel stream through the turns 31 or the jacket 86 is at a temperature well above that at which the valve 31 is set to open, the extra supply to the vaporizer is turned off. However, when the load used by the appliance 28 is increased and the rate of heat supply and transfer through the regulator 22 is not sufficient to vaporize all of the fuel, the temperature of the stream will quickly fall below the setting of the temperature responsive valve 30 if any liquid fuel is coming through the service line and the valve will open to supply extra fuel at service pressure to the mixer 45 and catalyzer bed 65 of the vaporizer 24.

Having thus described the preferred form of this invention, it will be apparent to those skilled in the art that various and further modifications such as the use of a separate supply of fuel gas; i. e., propane, to supply the vaporizer, which supply is fed through the temperature responsive valve, or the employment of a pressure responsive valve instead of a temperature responsive valve may be made without departing from the spirit and substance of the invention, as set forth

in the objects and the description, the scope of which is commensurate with the appended claims.

What is claimed is:

1. For use in a liquefied petroleum gas dispensing system a vaporizer comprising a flue, a catalyst bed disposed at the lower end of said flue, an annular space containing a fluid medium surrounding said flue, a second annular space surrounding and in communication with said first mentioned annular space, a conduit coil disposed in said second annular space, and means for supplying a mixture of fuel gas and air to the bottom of said flue below said catalyst bed.

2. For use in a liquefied petroleum gas dispensing system a vaporizer comprising a flue, a catalyst bed disposed at the lower end of said flue, an annular space containing a gas surrounding said flue, a second annular space surrounding and in communication with said first mentioned annular space at the top and bottom for convective circulation, a conduit coil disposed in said second annular space and shielded from said first space, and means for supplying a mixture of fuel gas and air to the bottom of said flue below said catalyst bed in a ratio less than that supporting flame combustion.

3. For use in a liquefied petroleum gas dispensing system a vaporizer comprising a flue, a catalyst bed disposed at the lower end of said flue, an annular space containing a fluid medium surrounding said flue, and having a wall dividing the space into two compartments in communication with each other at the top and bottom, a conduit disposed in said space in the compartment remote from the flue, and means for supplying a mixture of fuel gas and air to the bottom of said flue below said catalyst bed, said conduit being a portion of a service line conducting liquefied petroleum fuel from a place of storage to a point of use.

4. In a vaporizer for use in a liquefied petroleum gas dispensing system the combination including a flue, a catalyst bed disposed at the lower end of said flue, a pilot catalyzer bed disposed in intimate relationship with the first bed, a service conduit for liquefied petroleum fuel disposed in heat exchange relationship with said flue, and means for supplying a mixture of air and fuel gas to said catalyst beds in a ratio less than that supporting flame combustion, said means comprising a mixer for admitting a stream of fuel gas and air below said first bed,

and an element for supplying a separate stream of said fuel gas and air to the pilot bed continuously.

5. The method of dispensing liquefied fuel comprising educting a stream of liquid fuel from a container, reducing the pressure to vaporize a portion thereof, supplying heat to the stream to vaporize the remainder, reducing the pressure to a service pressure, withdrawing a portion of the flowing stream at service pressure, mixing the withdrawn portion with air, oxidizing the resultant mixture in the presence of a catalyst to supply heat to a larger catalyst bed, and withdrawing a second portion of the flowing stream intermittently when required, mixing said second portion with air and oxidizing it in said larger catalyst bed to produce heat which is supplied to said flowing stream after said first mentioned pressure reduction.

20 6. The method of dispensing liquefied fuel comprising educting a stream of liquid fuel from a container, reducing the pressure to vaporize a portion thereof, supplying heat to the stream to further vaporize same, reducing the pressure to a service pressure, withdrawing a portion of the flowing stream at service pressure, mixing the withdrawn portion with air, reacting the resultant mixture of fuel and oxygen from the air in the presence of a catalyst to warm a catalyst bed, and withdrawing a second portion of the flowing stream intermittently when required, mixing said second portion with air and reacting it in said warmed catalyst bed to produce heat and transferring the heat produced in the 25 warmed catalyst bed to said educted stream ahead of said reduction to service pressure.

7. The method set forth in claim 6 wherein the withdrawal of said second stream is controlled in relation to the temperature of the flowing stream at a point ahead of said reduction to service pressure and ahead of the point at which said transfer of heat occurs.

WILLIAM C. BUTTNER.
